COMBINATION DRILL AND REAMER

Ernst Sussman, Biery's Bridge Road, Bethlehem, Pa.

Filed Sept. 5, 1958, Ser. No. 52,512

Term of patent 14 years

(Cl. D54—4)

Figure 1 is a plan view of a combination drill and reamer, showing my new design;

Figure 2 is a front end view of the drill portion of the device;

Figure 3 is a view partly in perspective and partly in transverse section taken on line 3—3 of Figure 1; and

Figure 4 is a transverse sectional view taken on line 4—4 of Figure 1.

The characteristic features of my design for the combination drill and reamer disclosed reside in the portions having the four grooves and fluting as shown.

I claim:

The ornamental design for a combination drill and reamer, as shown and described.
